UNITED STATES PATENT OFFICE.

HERMANN ZANDER, OF STETTIN, GERMANY.

OIL PRESS WITH DISINTEGRATING MEANS.

Application filed June 3, 1926, Serial No. 113,586, and in Germany July 14, 1925.

For disintegrating the cake moulded in oil presses it has already been proposed to provide disintegrating devices directly combined with the oil press, the arrangement being such that the cake as it leaves the press passes through the disintegrating means lying in front of the orifice of the press being thereby highly subdivided, that is broken up into small pieces. It has also been proposed to cause the disintegrating apparatus to rotate with respect to the press, whereby the breaking up operation is considerably assisted.

Arrangements of this kind are not easy to fix, owing to their relatively complicated structure. They are located in front of the outlet orifice of the press and thus increase the height of such presses, which is already considerable, and also increase the length of the stroke.

The object of the present invention is to provide an oil press combined with a disintegrating means, in which these disadvantages are overcome by the disintegrating means which has the form of a grid being inserted at the bottom in the mouth of the press space, but so as to be capable of being raised, so that the opposing plunger, as it is raised before the press is filled, carries the grid-like set of cutters up with it. During the filling operation and during the pressing operation with the main plunger, which is now usually carried out in stages, the plungers descend, the grid following the opposing plunger until the grid-like set of cutters again rests on its support at the lower end of the press space. The opposing plunger continues to recede. During the application of pressure by the main piston the cake is forced out of the press, when it must pass through the disintegrating means which is now fixed at the bottom in the same, where it is disintegrated. The disintegrating apparatus may also be rotated.

The conditions will be particularly favourable, if the upper end of the opposing piston be provided with projections, such that the projections correspond to the spaces between the cutters of the disintegrating grid and are of the same height as the set of cutters. On the latter being raised a uniform pressing surface is thus provided which is formed by the end faces of the projections on the pistons together with the set of cutters lying between the same.

In the accompanying drawing a construc-

tional example of the invention is shown diagrammatically, the pressing space being circular. The pressing space may however be annular, in which case the portion shown in the drawing has a section through a cylinder being annular instead. Figure 1 is a longitudinal section and Figure 2 a transverse section on line I—I of Figure 1.

The pressing space is within the straining cylinder *b*. At the lower open end of the cylinder the set of cutters *d* rests on supports *a*, from which it is capable of being lifted. Below the straining cylinder *b* is the usual opposing plunger *k* and above the straining cylinder the filling and pressure plunger *z*, which are operated in a known manner. On the end of the plunger *k* are projections *h* the height and cross-sectional area of which correspond to the spaces between the cutters *m* on the set of disintegrating cutters *d*. On the plunger *k* entering the straining cylinder *b* at the commencement of a series of operations, the projections *h* will first enter the spaces in the disintegrating arrangement *d* between the cutters *m*, a flat face being thus formed. When continuing to move, the plunger *k* will raise the set of cutters *d* from the supports *a* and carry it along with it, until the top position is reached, say at the line *y*, when the filling operation and the motion of the piston *z* commence. On the plunger *k* descending the relative position of the set of cutters *d* and the plunger *k* is in no way altered until the set of cutters *d* has reached the position shown in Figure 1 and has come to rest on the supports *a* again. The set of cutters will then be arrested and will no longer follow the motion of the plunger *k*, so that the projections *h* on the latter will be withdrawn from the spaces between the cutters *m*. When it is desired to have short broken pieces, the set of cutters *d* will preferably be rotated. This may be effected by the supports *a* resting in circumferential slots in the straining cylinder *b*. It is then possible to act on one of the projections either by means of a rack and worm or by means of a lever having a slot or in any suitable manner thereby turning the supporting arrangement *a* and with it the set of cutters *m*, if stop members and recesses be provided for preventing the set of cutters *d* and the supports *a* from turning with respect to one another when in the position shown in Figure 1.

110
115

In order that the plunger *k* can move past the supporting members *a*, it is provided with a number of longitudinal grooves *x*, for instance three such grooves.

5 As will be seen from the drawing the disintegrating apparatus is contained in the pressing space itself so that it is necessary to provide intermediate structures between the pressing space and the opposing plunger.

10 What I claim is:

1. A disintegrating means for an oil press having a cylinder, comprising a set of cutters, means for supporting the said set of cutters at the lower end of the pressing cylinder so that they are capable of being removed, a plunger capable of sliding in the cylinder, an opposing plunger also capable of sliding in the cylinder and of carrying the set of cutters along with it during its 20 upward movement and of depositing it again on the supporting means, on the opposing plunger being withdrawn from the cylinder, whereby the cake is disintegrated on leaving the cylinder, as set forth.

2. The combination claimed in claim 1, 25 and having projections on the face of the opposing plunger, the cross-section and height of which are such that, on entering the pressing cylinder, they slide between the cutters of the disintegrating means and together with the said cutters form a flat surface, as set forth.

3. The combination claimed in claim 1, and having projections on the face of the opposing plunger, the cross-section and 30 height of which are such that, on entering the pressing cylinder, they slide between the cutters of the disintegrating means and together with the said cutters from a flat surface, and having longitudinal grooves in the 40 opposing plunger, to enable the said plunger to pass the supporting means for the disintegrating means in the cylinder, as set forth.

In testimony whereof I have signed my 45 name to this specification.

HERMANN ZANDER.
